UNITED STATES PATENT OFFICE.

CHARLES V. HENKEL, OF NEW YORK, N. Y.

PERPETUAL LEDGER.

SPECIFICATION forming part of Letters Patent No. 660,432, dated October 23, 1900.

Application filed October 23, 1899. Serial No. 734,487. (No model.)

To all whom it may concern:

Be it known that I, CHARLES V. HENKEL, of the city of New York, borough of Manhattan, in the county and State of New York, have invented new and useful Improvements 5 in Perpetual Ledgers, of which the following is a full, clear, and exact description.

This invention relates to a perpetual ledger of that class in which two clamping-sections 10 are arranged to move toward and from each other and are provided with pins for holding the pages forming the ledger, which pins are formed in sections sliding on each other as the clamping-sections move.

15 This specification is the disclosure of several forms of my invention, while the claims define the actual scope thereof.

Reference is to be had to the accompanying drawings, forming a part of this specification, 20 in which similar characters of reference indicate corresponding parts in all the views.

Figure 1 is a front view of the ledger thrown open, with parts broken away. Fig. 2 is a section on the line 2 2 of Fig. 1. Fig. 3 is a 25 section on the line 3 3 of Fig. 1. Fig. 4 is a section on the line 4 4 of Fig. 1. Fig. 5 is a section on the line 5 5 of Fig. 4. Fig. 6 is an exterior view of the key-hole plate, the view indicating by dotted lines the movement of 30 the bolt. Fig. 7 is a fragmentary elevation of one of the covers with parts in section. Fig. 8 is a detail view of one of the ferrules used on the cover. Fig. 9 is a sectional view 35 on the line 9 9 of Fig. 1. Fig. 10 is a cross-section of one of the sectional pins, and Fig. 11 is a cross-section illustrating a modification.

The ledger has a back or body portion 10, which is formed of a sheet of material with 40 laterally-turned end pieces 11 and which is bent transversely at the back proper to form a number of channels 12, disposed transversely and extending entirely across the back or body. These channels serve not only 45 to strengthen the back or body 10, but they also form guideways in which are received the ribs 14 of the clamping-sections which project from the rear surfaces. The outer ends of the extensions 11 are turned inwardly 50 to form flanges 16, embracing portions of the clamping-sections, as will be hereinafter described. Each clamping-section comprises a

back plate 15, on which plate the ribs 14 are formed, an outer side plate 15^a, an inner side plate 15^b, and a backbone or interior brace 55 15^c. The parts 15, 15^a, and 15^b are preferably constructed of wood, and the part 15^c is preferably constructed of iron or other metal. The back plates 15 are securely fastened to the rear edges of the inner side plates 15^b, and 60 the outer side plates 15^a are made to overlap the outer edges of the plates 15. If desired, the parts 15 and 15^b of each clamping-section may be constructed integral. The parts 15^a, 15^b, and 15^c are securely fastened together by 65 bolts 15^d, and the inner side plates 15^b are further fastened to the backbone or strengthening-bar 15^c by means of screws 15^e, as shown. By means of this construction the parts may 70 be effectively and conveniently bound.

In assembling the parts of the clamping-sections the outer side plates 15^a are first bound with a covering of leather or other substance and then fastened to the parts 15^c and 15^b by the bolts 15^d. After this the inner 75 side plates 15^b are bound so as to cover the heads of the bolts 15^d and hide the same. The ends of the back plates 15 are turned laterally to form extensions 17, which lie inside of the extensions 11 of the back or body of 80 the ledger and are embraced by the flanges 16, before described. The clamping-sections being thus constructed and mounted on the back or body of the ledger are movable toward and from each other to engage and disengage the leaves. It will be seen that any 85 number of leaves may be inserted and that the clamping-sections may be adjusted according to the number of leaves in the book.

For the purpose of steadyng the clamping-sections in their movement on the back or body I provide two transversely-disposed guide-plates 21, which overhang the back plates 15 of the clamping-sections and are held rigidly in connection with the body 10 90 by means of pins 22 or the like, which are fastened to the guide-plate and to the body. For the purpose of causing the two clamping-sections to move in unison I provide each section with one or more pivotally-connected 95 links 23, which links are connected in pairs to levers 24, fulcrumed on the back or body 10. The clamping-sections thus connected are provided with filing-pins for holding the 100

leaves, the pins being adapted to pass through orifices in the leaves, as ordinarily, and being formed in two slidably-connected sections 25 and 26. As shown in Fig. 10, these 5 sections are joined to slide by constructing the section 25 with undercut or dovetail grooves *a* therein, in which grooves slide dovetail prongs *b*, composing the section 26. The sections 25 and 26 of the pins are respectively 10 attached to the backbones or frame-bars 15^c of the clamping-sections, the pin-sections being extended through the inner side plates 15^b of the clamping-sections, as shown best in Fig. 3. It will thus be seen that the 15 section 25 is formed of a bar with the dovetail grooves *a* produced longitudinally therein and that the section 26 is composed of the three prongs *b*, as shown. The number of prongs and grooves is not essential, as will 20 be obvious. By this arrangement, therefore, the pin-sections are connected to slide and form a continuous pin running between the clamping-sections. No matter what position these clamping-sections occupy the pins 25 always present a uniform diameter to the leaves of the ledger, thus holding the leaves snugly and properly in place.

It is necessary to lock the clamping-sections in closed position, so that persons may not 30 surreptitiously remove the leaves from the ledger. This is accomplished (see Fig. 4) by means of two tubes 27 and 28, which are rigidly fastened to the clamping-sections. As shown, these tubes are formed integral with 35 the frame-bars 15^c of the clamping-sections, being projected through openings in the inner side plates 15^b. The tubes 27 and 28 are arranged to telescope the one within the other. The tube 27, being that which passes into the 40 tube 28, has fastened therein a head 29, provided with two spring-prongs 30. These spring-prongs engage with a bolt or bar 31, which is essentially rectangular in cross-section (see Fig. 5) and which has two of its opposite 45 faces formed with ratchet-teeth and adapted to be engaged by the spring-prongs 30. The remaining opposite faces of the bolt are plane, so that should the bar be turned to engage said plane faces with the spring-prongs 50 the bar will be permitted to move freely past the prongs. The disposition of the ratchet-teeth on the bolt or bar 31 is such that the bolt may be moved inward notwithstanding that the prongs 30 are engaged with 55 the ratchet-teeth, but these teeth will prevent the bolt from being drawn outward, unless, of course, the bolt is turned to disengage the ratchet-teeth from the spring-prongs. The bolt 31 is carried by the clamping-section to 60 which the sleeve 28 is attached, and the bolt is provided with a circular head 32, mounted to turn in the clamping-section and formed with a central guide-finger 33, projecting outward, and with openings 34 for the wards of 65 the keys to be used for the purpose of turning the bolt 31 to adjust the position of the ratchet-teeth with respect to the spring-

prongs. This head 32 is embedded in the side clamping-sections and is held in place by a key-plate 35, formed with an elongated 70 opening 36 to receive the key, which is indicated by dotted lines in Fig. 4 and which may be of any construction capable of performing the functions described. The turning movement of the bolt 31 and the head 75 thereof may, if desired, be limited by a pin 37, (see the dotted lines in Fig. 6,) which pin is arranged to project into a segmental slot 38 formed in the head.

A ledger thus constructed is especially 80 adapted for use in connection with the ledger-leaves shown in Figs. 3, 9, and 10. It should be understood that in connection with these perpetual ledgers there are employed ledger-leaves which are freely interchangeable, permitting a single binder to be used indefinitely by removing the leaves when they are full of accounts. Now this leaf 39 is provided at its inner portions with openings to receive the several parts 25, 26, 27, and 28. Outward of 85 the openings in which these parts are received the leaves 39 are formed with permanent corrugations 40, such corrugations extending longitudinally with the binder and vertically with respect to the ledger-page. These corrugations are formed without angular creases, thus preventing the breaking of the fiber of the paper, but are so produced as to permanently retain their form. Should the fiber of the paper be broken by the formation of 90 the corrugations, the page will soon tear at the crease and therefore be destroyed. The leaves thus constructed when placed in the ledger all lie intermeshed at the corrugations. By making the corrugations rounding, as 95 shown, thus avoiding a crease of any sort, I cause the leaves to lie open flat against the back or covers of the binder and at the same time prevent the shortening of the life of the leaf. Reference to Figs. 9 and 10 will show 100 that by these corrugations the ledgers open like a well-bound book and that the leaves 39 lie flat against the covers. The covers 41, as shown in the first nine figures, have their inner portions formed with round or roller-like 105 edges 42, which are seated to roll in correspondingly-formed cavities produced in the inner side plates 15^b of the clamping-sections, as shown best in Figs. 3 and 9. Each end of each roller-like edge 42 is covered with 110 a split ferrule 43. (See Fig. 7.) This ferrule is received on a reduced portion of the edge 42 and serves to hold in place the pins 44, which project beyond the edges and serve as 115 pintles for mounting the covers in bearings 45, attached to the ends of the clamping-sections. By this construction the covers are arranged to swing freely to open or closed position, and at the same time they are mounted upon the clamping-sections in a durable 120 and practically indestructible manner.

Fig. 11 illustrates a modified arrangement for the covers 41. According to this construction the covers are attached to the clamp-

ing-sections by sections of canvas 46 or like flexible material, such canvas being fastened between the outer side plate 15^a and the frame-bar 15^c, as shown.

5 Having thus described my invention, what I claim, and desire to secure by Letters Patent, is—

1. In a perpetual ledger, the combination of a back or body portion, clamping-sections 10 mounted to slide thereon toward and from each other by direct hand-pressure on the sections, a lever mounted on a constant fulcrum on the back or body portion, and links pivotally connected with the respective ends 15 of the lever and with the respective clamping-sections whereby the movement of one section imparts a like movement to the other.

2. In a perpetual ledger, the combination of a back or body portion formed of a strip of 20 material bent transversely to form channels therein extending throughout its width, and clamping-sections mounted on the back or body portion and formed with ribs on their rear surfaces, the ribs sliding in the channels.

25 3. In a perpetual ledger, the combination with two clamping-sections, of telescopic tubes respectively secured thereto, a head carried rigidly in the inner tube, a spring-prong attached to such head, and a bolt or bar attached to one of the clamping-sections, and engaged by the spring-prong, and having a plane side and a side with ratchet-teeth, the bolt or bar being mounted to turn.

4. In a perpetual ledger, the combination 35 with two clamping-sections, of telescopic tubes respectively secured thereto, a spring-prong held by one tube, and a bolt or bar held by one of the clamping-sections and capable of turning thereon, the bolt or bar having a plane side and a side with ratchet-teeth and being engaged by the spring-prong.

5. In a perpetual ledger, the combination 40 with two clamping-sections, of tubes secured to the clamping-sections and sliding one in the other, a spring-prong secured to the inner

surface of the inner tube, and a bolt or bar secured to the clamping-section carrying the outer tube and projecting into the said tubes, the said bolt or bar having two plane sides and two sides with ratchet-teeth with which the said spring-prongs engage, substantially as described.

6. A leaf for perpetual ledgers, the leaf having an inner portion adapted to be engaged by the ledger, an outer portion forming the 50 leaf proper and an intermediate portion formed with rounding corrugations produced permanently therein so that the leaves when superimposed, will lie intermeshed at the corrugations, for the purpose specified.

7. A leaf for perpetual binders, the leaf having permanent corrugations formed thereon and disposed vertically with respect to the leaf so that the leaves when superimposed will lie intermeshed at the corrugations.

60 8. A perpetual ledger, having a clamping-section comprising an outer side plate, a backbone or frame-bar, and an inner side plate, the three elements being rigidly fastened together, and a filing-pin extending through the 70 inner side plate and fastened rigidly to the backbone or frame-bar.

9. In a perpetual ledger, the combination of a back or body portion formed of a strip of material bent transversely to form channels therein extending throughout its width, clamping-sections mounted on the back or body portion and formed with ribs on their rear surfaces, the ribs sliding in the channels, transversely-disposed guide-plates bearing loosely on the inner faces of the clamping-sections, and pins attached to the guide-plates and to the back or body portion at the channels thereof to support the guide-plates rigidly on the back or body portion.
